BEVERAGE SERVING TRAY OR THE LIKE

Walter I. Bieger, Minneapolis, Minn., assignor to Arthur Salm Inc., Chicago, Ill., a corporation of Illinois

Filed May 21, 1963, Ser. No. 74,991

Term of patent 14 years

(Cl. D44—10)

Fig. 1

Fig. 2

Fig. 3

Fig. 4

Fig. 5

FIG. 1 is a side elevational view of a beverage serving tray or the like, showing my new design;

FIG. 2 is a top plan view thereof;

FIG. 3 is a sectional view thereof taken along the line 3—3 of FIG. 2;

FIG. 4 is a perspective view thereof; and

FIG. 5 is an end view thereof.

The essential features of the design are shown in full lines.

I claim:

The ornamental design for a beverage serving tray or the like, substantially as shown and described.
